(57) **CLAIM**

The ornamental design for a steering wheel, as shown and described.

DESCRIPTION

FIG. 1 is a front and right side perspective view of a steering wheel showing our new design;

FIG. 2 is a front and left side perspective view of the design shown in FIG. 1;

FIG. 3 is a rear and left side perspective view of the design shown in FIG. 1;

FIG. 4 is a rear and right side perspective view of the design shown in FIG. 1.

FIG. 5 is a front view of the design shown in FIG. 1;

FIG. 6 is a rear view of the design shown in FIG. 1;

FIG. 7 is a left side view of the design shown in FIG. 1;

FIG. 8 is a right side view of the design shown in FIG. 1;

FIG. 9 is a top view of the design shown in FIG. 1; and,

FIG. 10 is a bottom view of the design shown in FIG. 1.
